UNITED STATES PATENT OFFICE.

FREDERICK T. SNYDER, OF OAK PARK, ILLINOIS.

ELECTRODE-HOLDER.

1,254,080.

Specification of Letters Patent. Patented Jan. 22, 1918.

Application filed September 19, 1917. Serial No. 192,112.

To all whom it may concern:

Be it known that I, FREDERICK T. SNYDER, a citizen of the United States, residing at Oak Park, in the county of Cook and State of Illinois, have invented a certain new and useful Improvement in Electrode-Holders, of which the following is a full, clear, concise, and exact description.

This invention relates to improvements in electric furnaces and more particularly to electrode holders adapted for use in connection therewith.

There are two types of electrode holders now extensively used in the art, top holders and side holders. The present invention relates more particularly to side holders.

Heretofore the principal objection to the use of side holders has been the difficulty with which a good electrical contact between the holder and the electrode is secured owing to the unevenness of the surface of the latter. If the contact is not a good one, the holder becomes hot and may even be burned. While electrodes are designed to be straight throughout their lengths, round in cross section and smooth over their entire surfaces, they are not supplied to the trade in this form. On the other hand, their surfaces are generally uneven owing to their having been subjected to erosion from some cause or other; furthermore, they are also often-times warped and irregular in cross section, hence the difficulty in securing a good electrical contact with side gripping holders. Efficiency of course demands a good contact between the electrode and the holder, even if the holder be water cooled, for although the water cooling may prevent the holder from becoming excessively hot, the heat developed is at the expense of electrical energy. Then, too, a bad contact is likely to cause the electrode itself to become overheated adjacent the holder, thereby causing a serious deterioration of said electrode. Furthermore, excessive heat from the electrode may cause a water cooled holder to crack or break thereby causing considerable damage and necessitating a replacement of the holder.

An object of the present invention is to provide an electrode holder of the type de-

scribed which may be readily and quickly adjusted into clamping engagement with the sides of an electrode and which when adjusted will provide a good electrical contact therewith.

Another object is to provide an electrode holder of the type described which shall comprise a plurality of movable gripping blocks capable of adjusting themselves to the irregularities of an electrode as the same are moved into clamping engagement therewith. A further object is the provision of means whereby said pivoted gripping blocks may be moved into and out of clamping engagement with the electrode at a point distant therefrom.

Other objects and advantages will become apparent from the following description taken in connection with the accompanying drawings wherein the preferred embodiment of the invention is illustrated.

Figure 1 is a top plan view partly in section of an electrode holder constructed in accordance with the present invention.

Fig. 2 is a section on line 2—2 of Fig. 1.

Fig. 3 is a section on line 3—3 of Fig. 1.

Fig. 4 is a side elevation of an electric furnace showing an electrode holder applied thereto.

Fig. 5 is a front view of one of the gripping blocks, and

Fig. 6 is a detail view.

Referring more in detail to the drawings, an electric furnace is illustrated in Fig. 4 and is shown provided with an electrode supporting crane 1, by means of which adjustment of the electrode within the furnace may be effected, said crane being raised and lowered by means of a hand wheel 2 and its associated rack and pinion mechanism 3. The electrode is illustrated at 4 and is shown held at the end of the horizontal arm 5 of the crane, said electrode projecting downwardly therefrom into the furnace through a suitable opening in the roof thereof.

The construction at the outer end of the horizontal arm 5 will now be described in order to point out more clearly the manner in which the electrode is gripped and held in its predetermined adjusted position, reference being had more particularly to Figs.

1 and 2. The arm 5 preferably comprises a plurality of channel members 6 so disposed with relation to each other that the channels thereof face inwardly. A transversely disposed channel member is illustrated at 7 and is shown connecting the outer ends of the longitudinally extending members 6, said channel member 7 being bolted or otherwise rigidly secured in position. A second transversely disposed channel member is illustrated at 8 and is shown mounted intermediate the ends of the members 6, said channel member 8 being also rigidly secured in position by means of bolts or other suitable fastening means. It will thus be noted that a four-sided box or frame is provided at the outer end of the horizontally disposed arm 5 of the crane. Slidably mounted within the channels of the side members 6 and disposed transversely across the frame or box is a suitable cross head 9, said cross head being operable by means of the screw shaft 10 which extends rearwardly from the cross head 9 the full length of the horizontal arm 5 and which is provided at its end with a suitable hand wheel 10^a positioned at the side of the furnace, said hand wheel being insulated from the shaft 10 by means of a suitable insulating bushing 10^b shown more particularly in Fig. 6 of the drawings. The shaft 10 is journaled in the upright member of the crane and in a suitable boss 11 formed integral with the transverse channel member 8. The cross head 9 is provided with a suitable screw threaded boss 12 adapted to receive the inner screw threaded end 13 of the shaft 10. Suitable collars 14 are mounted on the bolt 10 at opposite ends of the boss 11 to thereby insure either an inward or outward movement of the cross head 9 when the hand wheel 10^a is turned. Suitable gussets 15 are provided at the outer ends of the cross head 9 and the channel member 7 substantially as shown. To these gussets 15 are pivoted, by means of suitable bolts 16, a plurality of gripping blocks 17. Four of these blocks are shown in the drawings but it is obvious that a greater or less number may be provided, if desired, without departing from the spirit of the invention. Each of the blocks 17 is provided with a plurality of rearwardly extending lugs 18 through which the pivot bolts 16 extend. The apertures 19 provided in these lugs 18 for the reception of the bolts 16 are preferably of larger diameter than the diameter of the bolts in order that each of the blocks may have a substantially universal movement so as to insure a good contact between each of said blocks and the electrode and an effective clamping of the same in position.

It will be noted from the above that each of the blocks 17 is vertically pivoted and

that owing to the clearance between the bolts 16 and the apertures in the lugs 18 through 23 which said bolts extend that said blocks in addition to being capable of a rocking motion on a vertical axis may also rock on horizontal axes. In other words, said blocks, owing to their loose pivotal connections, 70 have a substantially universal movement, as above pointed out. Thus, it will be noted that the blocks may readily adjust themselves around the surface of the electrode as they are brought into clamping engagement 75 therewith even though the electrode does not extend upwardly in a true vertical direction and even though the surface of the electrode is uneven or its cross sectional area irregular.

Each of the gripping blocks 17 is provided with a water cooling chamber 20 through which a cooling medium may be circulated in order to absorb the heat conducted to the blocks from the furnace by the electrode. These cooling chambers 20 in 25 the various blocks are shown connected by means of suitable flexible pipes 21 preferably covered with asbestos in order to protect them from the heat of the furnace. The inlet pipe for the cooling medium is illustrated at 22, the water as it passes therefrom being circulated through each of the blocks in successive order and then out through the outlet 23.

Current is supplied to the electrode by 95 means of flexible conductors 24 and 24^a which preferably extend through the channels of the frame. It will be noted that a housing for the protection of the flexibles is thus provided. These conductors 24 and 24^a 100 are bolted securely in contact with the gripping blocks 17 as at 25, the conductor 24 being bolted to the gripping blocks carried by the stationary support 7 while the conductor 24^a is bolted to the gripping blocks 105 carried by the movable support or cross head 9. While bolts are shown for the purpose of holding the flexibles in position, it is obvious that other means may be provided if desired. In order to provide for the inward 110 and outward movement of the gripping blocks which are pivoted to the movable cross head 9, the flexible which conducts current to the electrode through these blocks is preferably looped as at 26, said looped portions lying within the channel of the transversely disposed member 8. In this manner ample slack in the flexible 24^a is provided to permit of a maximum inward movement of said cross head.

In addition to the flexibles being securely held in contact with the blocks 17 by means of the bolts 25, said flexibles are also firmly clamped in contact therewith each time the blocks are moved into gripping engagement with an electrode. This clamping

of the flexibles against the blocks is effected by passing said flexibles between the back of said blocks and the pivot pins 16 as clearly shown in the drawings. By virtue of the blocks being loosely pivoted, as above pointed out, they are moved closer to the pivot pins when an electrode is gripped between them. This relative movement between the several blocks and their respective pivot pins during a gripping of an electrode in place clamps the flexibles firmly against said blocks. Thus, if desired, the bolts 25 may be dispensed with.

As the electrode is consumed, it is gradually fed downwardly by lowering the crane by means of the hand wheel 2 and its associated rack and pinion mechanism. When said crane has reached the downward limit of its travel, the operator, standing at one side of the furnace, grips the electrode between the top of the furnace and the horizontal arm 5 by means of a pair of tongs. Rotation of the other hand wheel 10 releases the electrode permitting the crane to be elevated after which the said electrode is again gripped between the pivoted blocks or contact members. The tongs are then withdrawn after which the electrode may be gradually fed downwardly as before. The electrodes employed are so constructed that they may be connected end to end, whereby a new section may be secured to the top of the section in use and the elongated electrode thus formed may be gradually fed downwardly as before. Additional sections are added to the top from time to time as a result of which each electrode is completely consumed.

The contact members are so supported that they may readily adjust themselves to the contour of the electrode thereby firmly holding the same in place and insuring good electrical contact regardless of irregularities in said contour. The various operations are readily performed, by operators standing on the charging platform 27, regardless of the temperature at the top of the furnace. The manual operating means is located at a point distant from the electrode gripping means whereby the operator is not exposed unnecessarily to the heat of the furnace. Heretofore it has been difficult to renew the electrode by reason of the fact that the electrode was clamped in place by clamping means which required manipulation above the furnace and would, therefore, expose the operator to the heat of the furnace. The blocks 17 may be readily replaced by smaller ones, should it become necessary or desirable to grip an electrode materially smaller than the one illustrated in the drawings.

It is obvious that various other changes

and modifications may also be made in the structure herein illustrated and described, and the right is therefore reserved to cover such changes and modifications as fall within the scope of the appended claims.

Having thus described my invention, what I claim as new and desire to secure by Letters Patent of the United States is:

1. An electrode holder of the type described, comprising a frame, a plurality of gripping blocks pivoted to said frame, a plurality of gripping blocks movable within said frame and means for adjusting said blocks into clamping engagement with an electrode.

2. An electrode holder of the type described, comprising a frame, a cross head slidably mounted therein, a plurality of blocks pivoted to said frame and to said cross head and means for adjusting said cross head to bring said blocks into clamping engagement with an electrode.

3. An electrode holder of the type described, comprising a plurality of vertically pivoted gripping blocks.

4. An electrode holder of the type described, comprising a plurality of vertically pivoted gripping blocks and means whereby said blocks may be adjusted into clamping engagement with an electrode from a point distant therefrom.

5. An electrode holder comprising a rigid box or frame, a plurality of blocks pivoted to said frame, a cross head slidably mounted in said frame, a plurality of blocks pivoted to said cross head and means for adjusting said cross head to bring said blocks into clamping engagement with an electrode.

6. An electrode holder of the type described, comprising a plurality of vertically pivoted water cooled gripping blocks.

7. An electrode holder of the type described, comprising a box or frame made up of side and end channel members, a cross head mounted within said frame and slideable in the channels of said side members, a plurality of gripping blocks pivoted to one of said end members, a plurality of gripping blocks pivoted to said cross head, and means journaled in the other of said end members for moving said cross head to bring said blocks into clamping engagement with an electrode.

8. An electrode holder of the type described, comprising a plurality of vertically pivoted gripping blocks, means whereby a cooling medium may be circulated therethrough, a plurality of electric conductors, means for securing said conductors to said blocks and means for adjusting said blocks into clamping engagement with an electrode.

9. An electrode holder of the type described, comprising a plurality of pivoted

- gripping blocks, coupling chambers in each of said blocks, flexible couplings connecting said chambers whereby a cooling medium may be circulated therethrough, electric conductors held in contact with said blocks and means for adjusting said blocks into clamping engagement with an electrode. 65
10. An electrode holder of the type described, comprising a box or frame made up of side and end channel members, a plurality of gripping blocks pivoted within said frame, a plurality of electric conductors extending through the channels of said side and end members and into contact with said blocks, and means for adjusting said blocks into clamping engagement with an electrode. 70
11. An electrode holder of the type described, comprising a stationary support and a movable support, a plurality of vertically pivoted gripping blocks carried by each of said supports and means located at a point distant from said supports whereby said movable support may be advanced to cause said blocks to firmly grip an electrode. 75
12. An electrode holder of the type described, comprising a stationary support and a movable support, gripping blocks carried by each of said supports, said blocks being loosely pivoted on vertical axes whereby they may readily adjust themselves to the irregularities of an electrode when they are moved into clamping engagement therewith. 80
13. An electrode holder of the type described, comprising a plurality of pivoted gripping blocks, electric conductors extending between said blocks and their pivots and means whereby the movement of said movable blocks into gripping engagement with an electrode acts to securely clamp said conductors in contact therewith. 85
14. An electrode holder of the type described, comprising a plurality of gripping blocks disposed above the furnace and means at the side of the furnace for operating said blocks to effect a clamping of the same about an electrode. 90
15. In an electrode holder of the type described, means positioned above the furnace for gripping an electrode, and means at the side of said furnace for operating said gripping means. 95
16. An electrode holder of the type described, comprising a plurality of longitudinally extending channel members terminating above the furnace, gripping blocks carried thereby and means for operating certain of said blocks to effect a clamping of an electrode between them and the remainder of said blocks, said means being controllable from a point at the side of the furnace. 105
17. An electrode holder for electric furnaces, comprising a plurality of water jacketed current conducting members arranged to contact directly with the electrode and a single means for causing all of said members to grip said electrode simultaneously. 110
18. An electrode holder for electric furnaces, comprising a plurality of electrode gripping members, means for adjustably mounting said members whereby they may move in any direction to adapt them to irregularities in the surface of said electrode and means for causing all of said members to grip said electrode simultaneously. 115
19. An electrode holder for electric furnaces, comprising a plurality of electrode gripping members, means for adjustably mounting said members whereby they may move in any direction to adapt them to irregularities in the surface of said electrode, and flexible conductors connected to said gripping members whereby the latter may conduct current to said electrode in any position of adjustment. 120
20. An electrode holder, comprising side channel members, a plurality of universally adjustable contact members supported thereby and flexible conductors connected to said contact members and arranged within the said channels whereby they are protected from the heat of the furnace. 125
21. An electrode holder, comprising two pairs of pivoted contact members, said members being arranged to move about substantially parallel axes and forming two sets of toggle members, and means for moving one pair of members relatively to the other pair to cause them to grip an electrode with a toggle action. 130
22. An electrode holder, comprising a plurality of contact members disposed above the furnace, and manually adjustable means connected therewith and located at the side of said furnace for operating said members, said manual means being insulated from said holder. 135
23. An electrode holder comprising a plurality of contact members disposed above the furnace, means for varying the relative positions of said members, a screw shaft associated with said means and a hand wheel at the side of said furnace for operating said screw shaft. 140
24. An electrode holder of the type described, comprising a plurality of relatively movable supports, a loosely mounted gripping block carried by each support, and electric conductors extending between said blocks and their supports whereby movement of said blocks into gripping engagement with an electrode acts to clamp said conductors in contact with said blocks. 145
25. An electrode holder comprising two pairs of pivoted contact members, said members being arranged to move about substan- 150

- tially parallel axes and forming two sets of toggle members, means for positively moving one pair of members toward and away from the other pair to cause them to grip 15
5 an electrode with a toggle action and to release the same.
26. An electrode holder comprising a plurality of electrode contact members, and means for causing said members to simultaneously grip the electrode, said means serving also to withdraw one of said members to insure relaxation of said grip. 20
10
27. An electrode holder comprising a plurality of electrode contact members and means for positively moving certain of said members toward and away from the electrode to cause said members to grip and release said electrode. 25
15
28. An electrode holder for electric furnaces comprising a plurality of water jacketed current conducting members arranged to contact directly with the electrode and means for positively withdrawing said members from said electrode to release the same. 20
20
- In witness whereof I hereunto subscribe 25
my name this 15th day of September, A. D.
1917.

FREDERICK T. SNYDER.
